RUTH B. OPPENHEIMER, OF CRESTWOOD, NEW YORK

HAIR DEVICE

Application filed February 14, 1929. Serial No. 339,795.

My present invention relates generally to hair devices, and has particular reference to barrettes.

One of the objects is to provide a device which will facilitate the support of the bun or knot of hair which is frequently worn by women at the back of the head, particularly of late. It is customary, as it has been for generations, to support such bun by means of hairpins. Where the hair is of limited 10 length, or where it is relatively heavy, regardless of length, a source of great annoyance lies in the failure of the hairpins to remain in place. As a matter of fact, the likelihood of hairpins coming loose or falling 15 out by accident is always an incident to their use, and is particularly prevalent where the bun to be supported thereby is positioned at the base of the skull in accordance with the present custom.

A more particular object of my invention is to provide means for minimizing, if not entirely preventing, the accidental displacement, loosening, or loss of hairpins, when 20 used for this purpose, and thereby preventing any loosening of the bun; and in accomplishing this object I have resorted to the magnetic susceptibility of the hairpins nowadays in common use.

More particularly, my invention resides in the provision of a barrette which is so constructed as to be applicable in a removable manner to the hair at the interior of the bun to be supported, the barrette including a 25 body of magnetized metal whereby metallic hairpins, upon contacting with the same, will be retained in position by magnetic attraction.

Other features of my invention reside in 30 the construction which renders the manufacture of my device extremely simple and inexpensive, which enables the magnetic qualities to remain operative for a maximum period of time, and which renders the day-by-day employment of the device a simple and unobjectionable matter.

For the attainment of the foregoing objects and such other objects as may herein-after appear or be pointed out, I have constructed a device embodying the features of

my invention and illustrated in the accompanying drawings in which—

Figure 1 is a perspective view of a barrette of the present character;

Figure 2 is a side view of the rear of a 55 woman's head, showing the manner in which the barrette is applied;

Figure 3 is a view similar to Figure 2, showing the ultimate disposition of barrette, bun, and hairpins; and

Figure 4 is a front elevational view of the barrette in closed condition, showing a preferred form of construction.

A piece of magnetically permeable metal, such as steel, is bent into arcuate shape, preferably in conformity with an ellipse. In Figure 1 I have shown a C-shaped body 10 constructed in this manner. This body is preferably of relatively small cross-section, is approximately one to two inches in horizontal length, and about three-fourths to one and one-half inches in height. This body is adapted to be employed with its free ends 11 and 12 downwardly for a purpose presently to be described.

Associated with this body and extending between the opposite sides 13 and 14 thereof is a suitable fastening means or clasp arrangement whereby the barrette may be removably associated with a bundle of hair.

In accordance with my invention, the body 10 is suitably magnetized, as by subjecting the same to a strong magnetic field, whereby metallic objects, such as hairpins, will adhere to a certain extent to the body 10; and the 85 clasp arrangement is of a magnetically re-luctive material, such as brass, bone, rubber, or the like.

For the sake of simplicity of structure and reduction of manufacturing cost, I prefer to provide a clasping device as shown most clearly in Figure 4. A pair of openings 15 are bored through the body at its side 14, and a set of similarly arranged openings 16 are bored through the opposite side 13. A resilient wire of magnetically impermeable material is doubled upon itself to provide the two substantially parallel portions 17, the bent mid-portion 18, and the free ends 19. The mid-portion 18 extends through the openings 16

and is thus positioned on the forward face of the body 10. The openings 16 are sufficiently large to enable the portions 17 to be swung into parallelism with the body 10 or rearwardly thereof as shown in Figure 1. The 5 openings 15 are positioned in such mutual adjacency with respect to the normal spacing of the portions 17 that the free ends 19 may not be threaded forwardly through the openings 15 unless the portions 17 are pinched together by a slight amount. In this way, the 10 ends 19 will press outwardly away from each other after they have been threaded through the openings 15, and the engagement thus 15 afforded will be sufficient to secure the portions 17 in the position of Figure 4 and thereby 20 clasp a mass or bundle of hair between the portions 17 and the rear surface of the body 10. This will serve to keep the barrette in position.

When the barrette is employed, a relatively 25 small bundle of hair lying close to the neck of the user is engaged by the barrette as shown in Figure 2 and as described in the preceding paragraph. It will be understood that the open ends 11 and 12 are directed downwardly and that the body 10 lies outwardly with respect to the head of the user. The 30 barrette is thus applied at a place which will ultimately be within the interior of the bun to be formed. This bun is thereupon formed in the usual manner, the barrette being completely 35 enclosed and concealed thereby, and hairpins are freely used in the usual way to hold the bun together and in place.

The greatest magnetic attraction will obviously exist adjacent to the free ends 11 and 12, and this is as it should be, for the reason that the hairpins which will contact with the 40 barrette body at these points will be extending with their points upwardly and will thus be the inverted hairpins which would normally be most likely to fall out by accident. Regardless of the particular point or points 45 at which the hairpin tips contact with the barrette body 10, a certain adhesion will take place which I have found is just sufficient to satisfactorily keep the hairpins from falling. At the upper portion of the body 10 a certain 50 amount of attraction will take place, less than at the open ends 11 and 12 but still sufficient to contribute to the general results desired. The attraction may be less at this point for the reason that the hairpins contacting 55 with the upper portion of the body 10 will most likely be arranged with their points downwardly so that accidental falling out would be comparatively unlikely.

It will thus be seen that the barrette is 60 easily applied and yet entirely unobjectionable. I have illustrated a form wherein it is designed to be totally concealed and invisible, but it is obvious that the body may be ornamented in any desired manner and 65 provided with a portion or portions adapted

to be left unconcealed for ornamental purposes. It must be borne in mind, however, that projections or the like, if formed of permeable material, would contribute toward loss of magnetism and would reduce the magnetic attraction where it is most needed.

I have found it most satisfactory to provide the barrette of unornamented material but of good quality steel. Its relatively small cross-section contributes to lightness and to its length of magnetic life. The cross-section is preferably rectangular, but may of course be circular or shaped in other ways to suit requirements.

Furthermore, although I have shown a 80 preferred type of clasp, it will be understood that any type of clasp or engaging device would be suitable so long as it is not composed of magnetically permeable material which would affect and impair the smooth unbroken 85 path of the magnetic flux. An ordinary elastic might in certain cases prove to be satisfactory although its method of application to a bundle of hair would be somewhat more difficult than that entailed with pivoted 90 clasps of the character illustrated and of the character heretofore in general use with respect to barrettes and the like.

It will be obvious that changes in the details herein described and illustrated for the 95 purpose of explaining the nature of my invention may be made by those skilled in the art without departing from the spirit and scope of the invention as expressed in the appended claims. It is therefore intended that 100 these details be interpreted as illustrative, and not in a limiting sense.

Having thus described my invention and illustrated its use, what I claim as new and desire to secure by Letters Patent is—

1. A barrette of the character described comprising a C-shaped body of magnetized metal adapted magnetically to attract metallic hairpins and hold the latter in contact therewith.

2. A barrette of the character described comprising a C-shaped body of magnetized steel, and means for applying said body with the open ends thereof downwardly to the interior of a knot of hair, whereby the hairpins forming and supporting said knot may contact with said body and be retained in position by magnetic attraction.

3. A barrette of the character described comprising a body of magnetized metal, and a pivoted clasp carried by said body for removably associating the latter with a bundle of hair, whereby metallic hairpins applied to said bundle and contacting with said body will be held in position by magnetic attraction.

4. A barrette of the character described comprising a body of magnetically permeable material, and a clasp of magnetically retractive material carried by said body for as-

sociating the latter with a knot of hair, whereby metallic hairpins applied to said knot and contacting with said body will be held in position by magnetic attraction.

5 5. A barrette of the character described comprising a C-shaped body of magnetized metal, and a clasp of magnetically retractive material extending across the body to enable the same to be removably associated with a 10 bundle of hair, whereby metallic hairpins applied to said bundle and contacting with said body will be held in position by magnetic attraction.

6. A barrette of the character described 15 comprising a C-shaped body of magnetized metal, and a clasp of magnetically retractive material extending across the body to enable the same to be removably associated with a bundle of hair, said clasp comprising a wire 20 doubled upon itself to provide free ends and a midportion, said midportion extending through one side of the body so as to enable said free ends to be brought into and out of association with the other side of said body.

25 7. For use with a knot or bun of human hair adapted to be retained in formation by metallic hairpins extending thereinto, a barrette of the character described comprising a C-shaped body of magnetized metal, and 30 hair-clasping means carried by said body to enable the removable application thereof in concealed stationary position within said bun with the open ends thereof downwardly.

In witness whereof I have signed this specification this 31st day of January, 1929.

RUTH B. OPPENHEIMER.
